UNITED STATES PATENT OFFICE.

CORNELIUS J. McCARTHY, OF DUNKIRK, NEW YORK.

TENDER FOR LOCOMOTIVES.

SPECIFICATION forming part of Letters Patent No. 790,650, dated May 23, 1905.

Application filed November 1, 1904. Serial No. 230,916.

To all whom it may concern:

Be it known that I, CORNELIUS J. McCARTHY, a citizen of the United States, residing at Dunkirk, in the county of Chautauqua and 5 State of New York, have invented a certain new and useful Improved Tender for Locomotives, of which the following is a specification.

This invention relates to an improved coal-gate for locomotive-tenders, which is made up of a plurality of sections connected by chains or other flexible means, so as to have a limited independent movement, whereby the gate is elevated gradually by raising the sections in 15 successive order.

The main objects of the invention are to provide for convenient exposure of coal in the coal-space and for elevating the gate gradually as the coal is used with but minimum effort. This is accomplished by connecting the sections so that they can be independently elevated in successive order, whereby but one section of comparatively narrow width and having but slight area in comparison with the total area of the gate is raised at one time against the friction of the coal, so that the gate is comparatively easy to raise. In order to still further decrease the friction, and thus render it easier to elevate, the gate may, if it is desired, be inclined slightly from the perpendicular, so the sections will have a tendency to slide diagonally on the coal instead of vertically in raising.

The invention also relates to certain details 35 of construction, all of which will be fully and clearly hereinafter described and claimed, reference being had to the accompanying drawings, in which—

Figure 1 is a side view of a locomotive-tender and a fragment of a locomotive, the tender being partially broken away at its forward end to show the improved coal-gate, the gate being shown in section. Fig. 2 is a front end view of the locomotive-tender, the gate being 45 shown closed. Fig. 3 is an enlarged detached front elevation of the gate. Fig. 4 is a horizontal section on line *a a*, Fig. 3. Fig. 5 is a transverse section on line *b b*, Fig. 6, through a fragment of one of the angle-irons and sliding plates to show the method of securing the

chains in place. Fig. 6 is a longitudinal section on line *c c*, Fig. 7, to show the method of securing the chains in place. Fig. 7 is a detached plan view of a fragment of one of the angle-irons and sliding plates. Fig. 8 is an enlarged detached plan view of one of the slotted plates for locking the chains in place. Fig. 9 is a transverse section through the shaft to show the method of securing the chains thereto. Fig. 10 is a central vertical section on line *d d*, Fig. 3. Fig. 11 is an enlarged detached front view of the improved gate, the gate being partially open. Figs. 12 and 13 are respectively detached plan and side views of the lower section of the gate. Fig. 14 is 65 an enlarged detached edge view of one of the angle-irons and sliding plates. Fig. 15 is an enlarged fragmentary plan view of one of the angle-irons, showing one of the openings through which the chains are passed. Fig. 16 70 is an enlarged detached end view of the horizontal shaft, its bearing-plate, and the means for rotating the shaft, the hand-wheel being shown in dotted lines. Fig. 17 is an enlarged detached end view of one of the angle-irons 75 and plates, showing the offset near the bottom edge thereof.

In referring to the drawings for the details of construction like numerals designate like parts.

The locomotive of which a fragment is shown in Fig. 1 is designated by the numeral 1 and may be of any of the usual and well-known types. The tender 2, which is coupled to the locomotive, has a coal-space 3. The forward 85 end of the coal-space or coal-box is closed by a coal-gate which is made up of sections connected by chains and adapted to be elevated in successive order to gradually enlarge the extent of the forward opening as the coal is used. The sections of the coal-gate are substantially duplicates of each other, with the exception of the bottom section. These duplicate sections are each composed of a substantially rectangular or main body portion 4, 95 which is of angular form in cross-section, (see Fig. 10,) and an angle-iron 5, which extends horizontally along and is riveted to the upper part of said body portion 4. It will be noted by referring to Fig. 4 that the body of 100

each section is lapped by the lower portion of the body of the next higher section in order to prevent any bulging of the sections of the gate from interior pressure of the coal. The 5 angle-irons 5 are bent outward at each end to provide a slot or slideway 6, (see Figs. 4 and 12,) in which the inwardly-extending flanges or parts of the vertical portions of a substantially U-shaped angle-iron 7, riveted to the 10 lining 8 of the coal-space, extend. The lower body-section of the gate comprises a body portion 9, which is cut away to leave a space 10 beneath the gate, which is always open, (see Fig. 3,) and an angle-iron 11, which is similar in contour to the angle-irons 5. The sections are elevated by chains 12, preferably two in number, which are fastened at their lower ends to eyebolts 13, attached to the angle-iron 11 of the bottom section, and at their upper extremity to a transverse shaft 14, which is journaled at or near the upper forward corner of the tender and constitutes a windlass for the chain. The sections of the gate, with the exception of the bottom section, are connected together by chains 15 for the purpose of maintaining them in proper separated condition when the gate is fully down, as shown in Fig. 3, or partially elevated, as shown in Fig. 11. The chains 15 are fastened at their 20 upper ends by eyebolts 16 to the horizontal portion of the U-shaped angle-iron 7 and at their lower ends to the angle-irons 5 of the section immediately above the bottom section by eyebolts 17. (See Fig. 10.) These chains 25 pass through openings in the angle-irons of each of the sections to which their lower ends are secured, and said sections are locked to the chains against sliding by slotted plates 30 18. The openings in the angle-irons 5, through which the chains 15 pass, are shaped in the cross form 19, (shown in Fig. 15,) and the slotted plate 18 (shown in Fig. 8) is fitted on one of the chain-links, with the link extending through the slot 20, as shown in Figs. 5 and 6. 35 The slotted plate 8 is then fastened by rivets 21 or other suitable means to the angle-iron. The shaft 14 is rotated to wind or unwind the chains 12 by a hand-wheel 22 and is locked in its position to hold the sections in any position to which they may be elevated by a ratchet 40 23, mounted on the shaft 14, which is engaged by a pawl 24. A lever 25 is provided which has a pawl 26 in engagement with the ratchet and is utilized to start the shaft when it is 45 stuck or works hard from clogging through the weight of the coal. It will be noted by referring to Fig. 10 that the gate is inclined slightly from the perpendicular, so that it is easier to elevate. The sections of the gate are 50 thus arranged so that they each have a limited independent movement and contact with and are adapted to elevate the next higher section by a continuation of the upward movement as the limit of their independent movement. The advantage of this is that but one

section of comparatively small area is elevated at a time against the friction of the coal instead of the entire gate, so that it is fairly easy to lift up the gate by successively raising the sections as the coal is used. If desired, the body portion 4 of each section may be bent or offset near the bottom edge thereof, as shown in Fig. 17, instead of immediately below the angle-irons 5. 70

The slideway 6 is sufficiently wider than the flanges of the U-shaped angle-iron 7 to permit the sections to rock or tilt slightly, and so fit closely one upon the other when the gate is opened, and thus prevent any dust or dirt from lodging between the sections or passing through and clogging them. 80

I claim as my invention—

1. In a device of the class described, the combination with a coal-box of a locomotive-tender, of a gate slidably mounted in the front 85 of the tender and composed of a series of connected sections, each of which is slideable throughout its length for a limited distance independently of other sections.

2. In a device of the class described, the combination with a coal-box of a locomotive-tender having a slideway at its front, of a transverse gate slidably mounted in the slideway at the front of the tender and composed of a series of sections and chains connecting said 95 sections.

3. In a device of the class described, the combination with a coal-box of a locomotive-tender having a slideway, of a transverse gate 100 slidably mounted in the slideway of said tender and made up of independent sections each consisting of a body and an angle-iron fastened to said body. 100

4. In a device of the class described, the combination with a coal-box of a locomotive-tender, of a gate slidably mounted in the front 105 of the tender and made up of independent sections each consisting of a body and an angle-iron fastened to said body and chains passing through and connecting said sections. 110

5. In a device of the class described, the combination with a coal-box of a locomotive-tender of a gate slidably mounted in the front of the tender and made up of independent sections each consisting of a body and an angle-iron 115 fastened to said body, and chains passing through the angle-irons for connecting said sections.

6. The combination with the coal-box of a locomotive-tender, having an angle-iron secured to the sides of the lining of said coal-box, of a gate made up of independent sections and having slotted ends into which the projecting parts of the angle-irons extend. 120

7. The combination with a coal-box of a locomotive-tender, of an angle-iron secured to the sides of the lining of said coal-box, and a gate made up of independent sections each consisting of a body and an angle-iron which are separated at the ends to provide slots in which 125 130

the angle-iron attached to the coal-box lining projects.

8. In a device of the class described, the combination with the coal-box of a locomotive-tender, of a coal-gate composed of a series of connected sections each having a limited independent movement whereby but one section is elevated at one time against the friction of the coal.

9. In a device of the class described, the combination with the coal-box of a locomotive-tender, of a coal-gate composed of a series of connected and lapping sections each having a limited independent movement whereby but

one section is elevated at one time against the friction of the coal and each section is adapted to contact with the next higher section at the limit of its independent movement.

10. The combination with a coal-box of a locomotive-tender, a U-shaped angle-iron attached to the lining of the coal-box, a gate made up of sections slidably mounted on parts of said U-shaped angle-iron and chains connecting the sections of said gate and fastened at their upper ends to the U-shaped angle-iron.

11. In a device of the class described, the combination with the coal-box of a locomotive-tender, of a coal-gate composed of a series of connected and lapping sections each having a limited independent movement whereby but one section is elevated at one time against the friction of the coal and means for elevating said sections including a rotatable shaft and chains connecting at their respective ends to the shaft and the bottom section of the gate.

12. In a device of the class described, the combination with the coal-box of a locomotive-tender, of a coal-gate composed of a series of lapping sections each having a limited independent movement and means for elevating said sections including a rotatable shaft, a ratchet on the shaft, a pawl engaging said ratchet and chains connecting at their respective ends to the shaft and the bottom section of the gate.

13. In a device of the class described, the combination with the coal-box of a locomotive-tender, of a coal-gate composed of a series of lapping sections each having a limited independent movement and means for elevating said sections including a rotatable shaft, a ratchet on the shaft, a lever having a pawl engaging with the ratchet and chains connecting at their respective ends to the shaft and the bottom section of the gate.

14. In a device of the class described, the combination with the coal-box of a locomotive-tender, of a coal-gate composed of a series of lapping sections each having a limited independent movement and means for elevating said sections including a rotatable shaft, a ratchet on the shaft, a pawl engaging said ratchet, a lever having a second pawl also engaging the ratchet and chains connecting at

their respective ends to the shaft and bottom section of the gate.

15. In a device of the class described, the combination with the coal-box of a locomotive-tender, of a coal-gate composed of a series of lapping sections each having a limited independent movement and means for elevating said sections including a rotatable shaft, a ratchet on the shaft, a pawl engaging said ratchet, a lever having a second pawl also engaging the ratchet, a hand-wheel on the shaft and chains connecting at their respective ends to the shaft and the bottom section of the gate.

16. In a device of the class described, the combination with a coal-box of a locomotive-tender of a gate slidably mounted in the front of the tender and made up of independent sections each consisting of a body and an angle-iron fastened to said body and having an opening in the form of a cross, chains passing through said cross-shaped openings and slotted plates fitted on links of the chains and fastened to the angle-irons.

17. In a device of the class described, the combination with a coal-box of a locomotive-tender, of a gate slidably mounted in the front of the tender and made up of independent sections each consisting of a body and an angle-iron fastened to said body and chains passing through and connecting said sections and plates secured to the angle-irons for preventing movement of the sections on the chains.

18. In a device of the class described, the combination with a coal-box of a locomotive-tender, of a gate slidably mounted in the front of the tender and made up of independent sections each consisting of a body and an angle-iron fastened to said body and chains passing through and connecting said sections and slotted plates secured to the angle-irons for preventing movement of the sections on the chains.

19. The combination with the coal-box of a locomotive-tender having an angle-iron secured to the sides of the lining of said coal-box, of a gate made up of connected sections slidably mounted between parts of said angle-iron.

20. The combination with the coal-box of a locomotive-tender having an angle-iron secured to the sides of the lining of said coal-box, of a gate made up of connected sections slidably supported by said angle-iron.

21. The combination with a coal-box of a locomotive-tender, of a U-shaped angle-iron attached to the lining of the coal-box and a gate made up of sections slidably mounted on said U-shaped angle-iron.

22. A tender having a coal-space provided with a front opening and a vertically-slidable coal-gate for closing said front opening comprising a plurality of yieldingly-connected sections.

23. A tender having a coal-space provided with a front opening and a vertically-slidable

coal-gate for closing said front opening comprising a plurality of connected sections.

24. A tender having a coal-space provided with a front opening and a vertically-slidable coal-gate for closing said front opening comprising a plurality of connected sections each having a limited independent vertical sliding movement.

25. A tender having a coal-space provided with a front opening and a vertically-slidable coal-gate for closing said front opening comprising a plurality of sections each being movable partly independently and partly in common with other sections.

26. A tender having a coal-space provided with a front opening and a vertically-slidable coal-gate for closing said front opening comprising a plurality of vertically-slidable connected sections which are substantially similar with the exception of the lower section, said lower section having a portion cut away to provide a space beneath the gate which is always open.

27. In a device of the class described, the combination with the coal-box thereof, of a coal-gate composed of a plurality of sections of angular form in cross-section.

28. In a device of the class described, the combination with the coal-box thereof, of a coal-gate composed of a plurality of sections each consisting of a rectangular body portion, and an angle-iron extending horizontally along and riveted to the upper part of said body.

29. In a device of the class described, the combination with the coal-box thereof having a slideway portion, of a coal-gate composed

of a plurality of sections each consisting of a body portion and a horizontal angle-iron secured to said body and having its ends bent to provide a slot in which the slideway portion of the coal-box engages.

30. A tender having a coal space or box and a coal-gate made up of slidable sections and means for independently elevating said sections in successive order whereby the gate is gradually raised by sections with a minimum of effort, substantially as set forth.

31. A tender having a coal space or box and a coal-gate made up of slidable sections, and means for independently elevating said sections one by one in successive order whereby the gate is gradually raised by sections with a minimum of effort, substantially as set forth.

32. A tender having a coal space or box and a coal-gate slidably mounted at the front of said coal space or box and at least slightly inclined from the perpendicular and toward the body of the coal substantially as set forth.

33. A tender having a coal space or box and a coal-gate for closing the entrance to said coal space or box, said gate being composed of a plurality of vertically-slidable connected sections at least nearly all of which are adapted to have a slight independent movement and to raise the next higher section by a continuation of the upward movement at the termination of said independent movement, substantially as set forth.

CORNELIUS J. McCARTHY.
